CLAIM

The ornamental design for a bottle, as shown and described.

DESCRIPTION

FIG. 1 shows a perspective view of a design for a bottle. FIG. 2 shows a side view of FIG. 1. FIG. 3 shows a top view of FIG. 1; and, FIG. 4 shows a bottom view of FIG. 1. The broken lines in the drawings illustrate the portions of the bottle and a bottle cap that form no part of the claim.

1 Claim, 4 Drawing Sheets
